J. F. GRIFFIN

LOCOMOTIVE SMOKE BOX WALL CONSTRUCTION

Filed July 16, 1925

INVENTOR.
JOSEPH F. GRIFFIN.

BY *O. V. Thiele*

ATTORNEY.

UNITED STATES PATENT OFFICE.

JOSEPH F. GRIFFIN, OF TEANECK, NEW JERSEY, ASSIGNEE TO THE SUPERHEATER COMPANY, OF NEW YORK, N. Y.

LOCOMOTIVE-SMOKE-BOX WALL CONSTRUCTION.

Application filed July 16, 1925. Serial No. 44,020.

My invention relates to locomotives and has particular reference to a form of construction applicable to smoke-box walls where it is necessary for conduits to pass there-through.

In locomotive operation it is necessary in order to obtain the necessary capacity to work the boiler under forced draft, and this is usually obtained by the ejector action of the exhaust steam from the locomotive engine, discharged from an exhaust pipe located in the locomotive smoke-box directly under an extension of the locomotive stack, which passes through the smoke-box wall. In order to maintain the required draft through the boiler flues, it is necessary that the smoke-box of the locomotive be kept air-tight, a condition which is difficult to obtain and maintain because of leakage which develops at the points where the locomotive stack and other necessary conduits must pass through the smoke-box wall.

It is the general object of my invention, therefore, to provide an improved form of construction for smoke-box walls, whereby conduits may pass there-through without being subject to leakage at the joints where they pass through the smoke-box walls, although it will be evident as the description proceeds that my invention may be applied to other forms of construction where similar conditions prevail.

In the standard form of stack construction the stack is divided into upper and lower sections, the upper section being formed with an external flange intermediate its ends which is secured to the exterior of the smoke-box shell around an opening in the latter through which the flanged lower end of the upper stack section extends. The lower stack section removably secured to this flanged end forms a skirt extending downwardly to a point just above the draft creating exhaust nozzle. The form of the upper stack section makes it extremely difficult, if not impossible, to machine the lower face of the stack flange to the contour necessary to bring it into close contact along its entire circumference with the curved smoke-box sheet, and this difficulty is enhanced by the fact that while the smoke-box sheet is theoretically a true circle in cross-section, there is very often as a matter of practice considerable variation from this theoretical form by the time the smoke-box sheet is in its assembled position. For this reason the lower flange face must, in accord-

ance with the present practice, be laboriously chipped by hand until it conforms as closely as possible to the outline of the sheet after which it is secured in place usually by means of bolts and as tight a joint as possible secured by the use of some form of flexible packing held in position by compression between the sheet and the flange. 60

The form of construction just described does not provide a satisfactorily tight joint between the stack and the smoke-box wall and by my invention I provide a form of construction in which the general form of stack usually employed is retained, but which provides a novel form of juncture between the stack and the smoke-box wall, whereby the usual troublesome curved joint is eliminated and a form of joint provided which may be easily kept airtight. 65

In accordance with my invention, as illustrated in the accompanying drawing, I provide over the opening 10 in the smoke-box sheet 11 a member 12 having a wall portion 13, and a flat inwardly extending flange 14, extending inwardly to a central opening conforming substantially to the cross section of the stack. The lower end of the wall portion of the member 12 may, because of the form of the member, be machined readily to fit the curved surface of the sheet 11 and is welded by any of the well-known methods to the wall 11, as at 15, the welded joint forming a permanent and air-tight joint between the smoke-box wall and the member 12. 70

It will be obvious, however, that because of the welded joint at 15 the expense of machining the member 12 may not necessarily be resorted to, as the weld will serve to effectively close any openings caused by inequalities between the smoke-box wall and the member 12, and for this reason if the latter is cast it may be cast to approximately the form required and thereafter welded in place without either machining or chipping. In the form illustrated, the flange 14 is upset about 80 the central opening to form a transverse web 16, having an upper flat bearing face 17, and a similar lower face 17a, but it will be apparent that the upsetting may be omitted and the bearing faces formed directly on the flange. 85

The upper portion of the stack is formed by a member 18 having a flange 19 at the bottom thereof, which is suitably recessed to fit the upper bearing face 17 of the flange 14. The lower stack extension 20 is formed with 100 105 110

a flange 21, similar in form to the flange 19, and similarly recessed to fit the lower bearing face 17^a of the flange 14. The opening 10 is made large enough to permit the flange 21 to pass there-through and the stack is assembled by fitting the upper and lower portions thereof respectively over the upper and lower faces of the flange 14, after which they are held in position by means of suitable fastenings, such as the through bolts 22, passing through suitable openings in the flanges 19 and 21, and in the intermediate flange 14. The flat bearing surfaces 17 and 17^a of the flange 14, as well as the corresponding recesses in the flanges 19 and 21, may readily be machined and finished so that a tight metal to metal joint may be made, or if desired, a copper or other efficient form of gasket may be used in making the joint.

It will thus be seen that by very simple and inexpensive form of construction a readily removable stack of the desired form may be provided which will secure a tight joint at the smoke-box wall, and which will materially reduce the expense both of manufacture and of maintenance.

While I have described my invention in connection with a locomotive stack, it is to be understood that it is not limited solely to this use, but is applicable to such forms of construction as may fall within the purview of the appended claims.

I claim:

1. In apparatus of the class described, a locomotive smoke-box sheet having an opening therein, a member encompassing said opening and welded to said sheet, said member including a flange portion extending inwardly to and provided with upper and lower bearing faces around a central opening and above the opening in said sheet, a stack member having a lower end engaging said upper face, a second stack member having an upper end extending through the opening in said sheet and engaging said lower face, and clamping means extending through said stack members and said flange to hold the former in engagement with the latter.

2. In apparatus of the class described, a locomotive smoke-box sheet having an opening therein, a member encompassing said

opening and welded to said sheet, said member including a flange portion extending inwardly to and provided with upper and lower plane bearing faces around a central opening and above the opening in said sheet, an upper stack member having a flat end engaging said upper face, a lower stack member having a flat end extending through the opening in said sheet and engaging said lower face, and clamping means extending through said stack members and said flange to hold the former in contact with the latter, whereby a flat-surfaced joint is secured there-between.

3. In apparatus of the class described, a locomotive smoke-box sheet having an opening in the top thereof, a hollow member encompassing said opening and extending thereabove, one end of said member conforming substantially to the curvature of said sheet and being welded thereto, the other end terminating in an inwardly extending flange having upper and lower bearing faces around a central opening and above the opening in said sheet, an upper stack member having an end engaging said upper face, a lower stack member having an end extending through the opening in said sheet and engaging said lower face, and clamping means passing through said stack members and said flange to hold the former in engagement with the latter.

4. In apparatus of the class described, a locomotive smoke-box sheet having an opening in the top thereof, a hollow member encompassing said opening, one end of said member conforming substantially to the curvature of said sheet and being welded to the upper side thereof, the other end terminating in an inwardly extending flange having plane upper and lower bearing faces around a central opening and above the opening in said sheet, an upper stack member having a flat end engaging said upper face, a lower stack member having a flat end extending through the opening in said sheet and engaging said lower face, and clamping means extending through said stack members and said flange to hold the former in contact with the latter, whereby a flat-surfaced joint is secured there-between.

JOSEPH F. GRIFFIN.
